UNITED STATES PATENT OFFICE.

BRYANT H. BLOOD, OF HARTFORD, CONNECTICUT, ASSIGNOR TO PRATT & WHITNEY COMPANY, OF NEW YORK, N. Y., A CORPORATION OF NEW JERSEY.

DEVICE FOR LAPING CYLINDERS.

Original application filed September 26, 1921, Serial No. 503,163. Divided and this application filed June 25, 1923, Serial No. 647,563. Renewed June 4, 1926.

The invention relates to an improved apparatus for lapping cylindrical surfaces. Particularly, the invention relates to an apparatus for simultaneously lapping the cylindrical surfaces of a plurality of gages.

This application is a continuation in part of my copending application Serial No. 447,027, filed February 23, 1921, and a division of my copending application Serial No.

10 503,163, filed September 26, 1921.

An object of the present invention is to provide means to mount the articles being lapped in a holding member, or spider, disposed in a symmetrical group, and in such a manner that they may be rotated about their individual axes without parts of the holding member coming into contact with their cylindrical or end faces.

Another object of the invention is to provide means to rotatably mount the cylinders being lapped in the holding member so that their axes are non-radial of the holding member but disposed so that they are tangent to a circle concentric to the axis of the holding member.

Another object of the invention is to provide a number of short arbors upon which the cylinders to be lapped may be individually mounted so that they may rotate freely thereupon, each arbor being held non-rotatably in the holding member but free to adjust itself toward or from one of the laps and adapted to be placed with either end pointing outward of the holding member.

A further object of the invention comprises a construction permitting rotation of the holding member between the two opposed laps about its own center and also bodily in a circle concentric with the rotatable lap. Preferably, both movements of the holding member are induced by the rotary movement of one of the laps and by means constraining the holding member to a definite planetary or orbital path.

With these and other objects in view, my invention consists in the features of construction and operation set forth in the following specification and illustrated in the accompanying drawing.

In the accompanying drawing annexed hereto and forming a part of this specification, I have shown my invention embodied in and adapted to be carried out in a gage lapping machine but it will be understood

that the invention can be otherwise embodied and that the drawing is not to be construed as defining or limiting the scope of the invention, the claims appended to this specification being relied upon for that purpose.

In the drawing:

Figure 1 is a sectional view in elevation of the parts forming the present invention; the section being taken on line 1—1 of Fig. 2.

Fig. 2 is a plan view of the apparatus with the upper or rotatable lap removed.

Fig. 3 is a detail sectional view of one of the articles being lapped mounted on its individual arbor.

Fig. 4 is an end view of the same.

In the above mentioned drawing, I have shown but one embodiment of a machine forming my invention which is now deemed preferable but it is to be understood that changes and modifications may be made within the scope of the appended claims without departing from the spirit of the invention.

Briefly, the machine forming my invention, in its broadest aspect comprises the following principal parts: first, a lower or stationary lap, the upper surface of which is carefully surfaced to a perfect plane and charged with a suitable abradant material; second, a rotatable lap mounted above the stationary lap and adapted to adjust itself as to parallelism relative to the lower lap, the lower surface of this upper lap being also carefully surfaced and charged with suitable abradant material; third, a holding member disposed between the laps wherein a plurality of articles to be lapped may be mounted and retained in a regular or systematic series;

fourth, a crank rotatably mounted in the lower or stationary lap and also in the holding member constraining the holding member to rotate about its center and to move bodily in a circle about the center of the lower or stationary lap; and fifth, arbors disposed symmetrically about the holding member upon which the articles may be rotatably mounted.

The method of operating the machine forming the present invention comprises the following principal steps; mounting the cylinders to be lapped in the holding mem-

ber individually on the arbors above referred to, and rotating one of the laps, preferably the upper one, while the holding member and cylinders are disposed therebetween, 5 continuing the lapping operation for a predetermined time, then removing the upper lap, and transposing or rearranging the relative positions of the cylinders in the group, and repeating the lapping and transposing operations alternately until identical diameters are obtained.

Referring more in detail to the figures of the drawing, at 10 is shown a suitable base upon which may be fastened by any suitable 15 means a lap 11. The upper surface 12 of this lap is surfaced to a perfect plane and is charged with a suitable abradant material. The lap 11 is provided with a central hole 13 for a purpose presently to be described. Above the stationary or lower lap 11 is a lap 15 which may be rotated by means of a shaft 16. The connection between the shaft 16 and the lap 15, as indicated by the screws 17 and the holes 18 25 through the plate 19 to which the shaft 16 is fastened, is such that the lap 15 may adjust itself as to parallelism with the surface 12 of the lap 11. The lower surface 20 of the rotatable lap 15 is also carefully surfaced so that it is perfectly plain and is charged with a suitable abradant material.

Disposed between the contiguous surfaces 12 and 20 of the two laps 11 and 15 is a holding member, or spider 25, most 35 clearly shown in Fig. 2. This is preferably circular and provided with a small hole 26 in its center in which a bearing member 27 may be disposed. Arranged about the periphery of the holding member or spider 40 25 are a plurality of articles A preferably symmetrically disposed about the center 26. These, as shown, are preferably disposed in elongated arcuate openings 31, four of these 45 openings being shown, each of which has four arbors 30 mounted therein upon which the articles are mounted. Preferably, the arbors 30 may be supported in position in slots 32 and 33 cut through the spider 25, one end of the arbors 30 being cut away on 50 either side as shown at 34 in Fig. 3 so that they will be non-rotatably held relative to the spider. Preferably, I make these arbors 30 of a steel rod of a diameter as shown at 35, one end, as referred to above, 55 being cut away to leave the end 34 with flat sides. The opposite end of the arbor 30 is screw threaded as shown at 36 upon which a nut 37 may be threaded and locked in position by small screws 38. The extreme 60 outer end 39 of the arbor may be circular and adapted to fit freely within one of the depressions 32. Between the head 35 and the adjustable nut 37 on the arbors 30 I may mount washers or spacing members 40, any thickness being used so that they will accom-

modate the particular length of gage being lapped. Preferably, the slots 32 and 33 are of the same width, and the parts 34 and 39 of the arbors 30 are of the same thickness so that the arbors 30 may be disposed in the spider with either end of the arbors 30 extending outward. Also the slots 32 and 33 are large enough to permit sliding movement of the arbors.

From this construction, it will be seen that any diameter of cylinders A may be mounted on the arbors 30 and rotatably held thereon by the spacing members 40 and the nut 37. Further, when mounted on the arbors 30, the articles A being lapped are held in a symmetrical series evenly spaced about the holding member or spider 25. The arbors 30 within the slots 32 and 33 are free to adjust themselves vertically toward or from either of the laps so that slight variations in diameters of the articles may be compensated for by slight vertical movement of the arbors.

In operation, the articles to be lapped are rotatably mounted individually upon their respective arbors, and the arbors disposed in position in the spider 25 while resting on lap 11. One end of a crank 50 projects through the bearing member 27, the opposite end of the crank 50 being disposed as shown in Fig. 1 in the hole 13 provided in the center of the stationary lap 11. With the parts so adjusted, the lap 15 is mounted so that it will rest upon the upper surfaces of the articles to be lapped. The shaft is then rotated by any suitable means, the lap 15 being free to adjust itself as to parallelism relative to the lapping surface 12 of the stationary lap 11 and at all times contacts with the upper surfaces of the larger articles being lapped. Rotation of the upper lap 15 by the shaft 16 tends to rotate the holding member or spider 25 in the same direction and the action of the short crank 50 or other suitable means in combination with the rotative action of the upper lap forces the holding member 25 not only to rotate about its own center 26 but also to rotate bodily about the center 13 so that it is bodily moved about the center of rotation of the laps 11 and 15 and also giving a free rotative movement about its own axis. As the articles are disposed non-radially, the effect of this rotative and planetary movement of the holding member causes a lapping movement of the articles A across the lapping surfaces 12 and 20 while the articles A are constantly rotating.

After the articles have been lapped a predetermined length of time while retained in one position in the holding member, the upper lap 15 is removed and the articles A in the holding member 25 are transposed or interchanged relative to each other, the upper lap 15 is then replaced and another lap-

ping operation takes place. These alternate lapping and interchanging operations may take place repeatedly until identical diameters are obtained on the cylinders and the 5 diameters are accurately lapped to a precise predetermined size.

In carrying out the interchanging or transposing operation, advantage may be taken of the plan disclosed in application 10 289,591 of W. E. Hoke filed April 12, 1919, to which reference may be had for a full description. The essential feature of this is that variations in diameters of the articles 15 are so distributed that the upper lap contacts only with the larger articles.

One method of transposing is diagrammatically shown in Fig. 2 in which the double arrows point to the articles which are moved and indicate also the positions to 20 which they are transposed. Simultaneously with the transposing of alternate cylinders to diametrically opposite positions, the cylinders may be turned end for end to further distribute variations in diameters of the cylinders 25 and to aid in obtaining absolute precision.

What I claim is:

1. A lapping device comprising in combination, a lower lap, an upper lap adapted 30 to rest upon and adjust itself relative to the articles being lapped, means for rotating one of said laps, a holding member for a plurality of articles disposed between said laps, said member being free to rotate about its 35 own axis, and means rotatably connecting said holding member to one of said laps whereby the axis about which the holding member rotates is held at a constant distance from the axis of the rotating lap.

40 2. A lapping device comprising in combination; a lower lap, an upper lap adapted to rest upon and adjust itself relative to the articles being lapped, means for rotating one of said laps, a holding member for a plurality of articles disposed between said laps, and means connected to the axis of one of the laps rotatably connecting said holding member to said lap whereby the axis about which the holding member may rotate is held at a constant distance from the axis of 50 the rotating lap.

3. A lapping device comprising in combination, a lower lap, an upper lap adapted to rest upon and adjust itself relative to the 55 articles being lapped, means for rotating one of said laps, a holding member for a plurality of articles disposed between said laps, and a short crank rotatably connecting said holding member to one of said laps whereby the axis about which the holding member may rotate is held at a constant distance from the axis of the rotating lap, and whereby said holding member is free to rotate about its own axis.

65 4. A lapping device comprising in combi-

nation, a lower lap, an upper lap adapted to rest upon and adjust itself relative to the articles being lapped, means for rotating one of said laps, a holding member disposed between said laps having a plurality of articles 70 symmetrically disposed therein, and means rotatably connecting said holding member to one of said laps whereby the axis about which the holding member may rotate is held at a constant distance from the 75 axis of the rotating lap, and whereby said holding member may rotate about its own axis.

5. A lapping device comprising in combination, a lower lap, an upper lap adapted to 80 rest upon and adjust itself relative to the articles being lapped, means for rotating one of said laps, a holding member for a plurality of articles disposed between said laps, and a short crank connected at one end to 85 the lower lap and at its other end to the holding member and rotatably connecting said holding member to said lower lap whereby the axis about which the holding member may rotate has a planetary movement at a constant distance from the axis of 90 the rotating lap.

6. A lapping device comprising in combination, a lower lap, an upper lap adapted to 95 rest upon and adjust itself relative to the articles being lapped, means for rotating the upper lap, a holding member for a plurality of similar articles disposed between the contiguous surfaces of said laps, and a short crank rotatably connecting said holding member to one of said laps whereby the axis about which the holding member may rotate is held at a constant distance from the axis 100 of the rotating lap and the articles in being lapped are adapted to pass over the entire 105 laps of said laps.

7. A lapping device comprising in combination, a stationary lap, a rotatable lap adapted to rest upon and adjust itself relative to the articles being lapped, and a holding member disposed between said laps adapted to hold a plurality of articles to be 110 lapped, arbors removably mounted on said holding member, said articles being rotatably mounted on said arbors.

8. A lapping device comprising in combination, a stationary lap, a rotatable lap adapted to rest upon and adjust itself relative to the articles being lapped, and a holding member disposed between said laps 120 adapted to hold a plurality of articles to be lapped in a symmetrical arrangement about said holding member, arbors symmetrically positioned on said holding member, said articles being rotatably mounted on said arbors.

9. A lapping device comprising in combination, a stationary lap, a rotatable lap adapted to rest upon and adjust itself relative to the articles being lapped, and a hold- 130

ing member disposed between said laps adapted to hold a plurality of articles to be lapped, arbors removably mounted on said holding member, said articles being rotatably mounted on said arbors, the axes of said arbors being tangent to a circle concentric with said holding member.

10. A lapping device comprising in combination, a stationary lap, a rotatable lap adapted to rest upon and adjust itself relative to the articles being lapped, and a holding member disposed between said laps, arbors retained in the holding member adapted to hold a plurality of articles to be lapped 15 in spaced relation to each other, said articles being rotatably mounted on said arbors and

engaging said arbors on the end faces of recesses formed in said articles.

11. A lapping device comprising in combination, a stationary lap, a rotatable lap adapted to rest upon and adjust itself relative to the articles being lapped, and a holding member disposed between said laps, slots formed in said holding member, arbors retained in said slots but permitted to adjust 25 themselves vertically to hold a plurality of articles to be lapped, said articles being rotatably mounted on said vertically adjustable arbors.

In testimony whereof, I hereto affix my 30 signature.

BRYANT H. BLOOD.
